ABRASIVE MACHINE

David Pronovost, Rosemont, Monreal, Quebec,
Canada

Application August 5, 1943, Serial No. 497,471

6 Claims. (Cl. 51—175)

The present invention pertains to a novel portable abrasive machine and resides in improvements on the apparatus shown in my U. S. Patent No. 2,289,932 of July 14, 1942.

The main object of the invention is to provide a machine having a pair of abrasive heads that set up equal and opposite reactive forces at any given instant of operation, so that the operator is not required to push the machine against the action of either head. This object is accomplished by mechanism that moves the heads oppositely to one another. The mechanism consists preferably of arms extending from the heads and joined to an operating shaft by crank connections spaced 180° apart around the shaft.

Each head may be half or full width of the machine frame, with its stroke adjusted accordingly.

Another object is to enable the machine, while operating on a floor, to work close to the walls. With this object in view, the overall width of the abrading heads is made somewhat greater than that of the machine frame and symmetrical therewith.

The invention is fully disclosed by way of example in the following description and in the accompanying drawing in which:

Figure 1 is a side elevation of the machine;

Figure 2 is a front elevation;

Figure 3 is a fragmentary plan view, and

Figure 4 is a similar plan view of a modification.

Reference to these views will now be made by use of like characters which are employed to designate corresponding parts throughout.

In Figure 1 is shown a suitable framework 1 mounted on casters 2. To a side of the framework is attached a push handle 3, and in a suitable position as on the top, is mounted a motor 4.

A countershaft 5 is journaled in the frame and carries a small pulley 6. The shaft 7 of the motor carries a small pulley 8 belted at 9 to a larger pulley 10 on the shaft 5. A driven shaft 11 is journaled in the frame near the lower end thereof and carries a large pulley 12 belted at 13 to the small pulley 6. Thus, the speed of the shaft 11 is considerably reduced from that of the motor shaft 7.

At opposite ends of the shaft 11, and preferably outside of the frame 2, are mounted disks 14, each carrying a projecting arm 15. To each arm is rotatably attached a bearing 16, and the bearings are 180° apart with reference to the axis of the shaft 11.

To each bearing is secured a forwardly extend-

ing arm 17, and the forward ends of these arms carry weighted heads 18 resting on the floor 19. The heads have convex surfaces 20 facing downward and covered with a suitable abrasive 21. Such abrasive may be sandpaper or, in some cases, closely packed metal teeth, or carbonate stone according to requirements.

In the operation of the device, the heads are always moving oppositely to one another because of their 180° spacing around the final driven shaft 11. Thus, their reactive forces balance each other, and the operator is not required to push against the reaction of either head.

In the construction shown in Figures 1, 2 and 3, each head is approximately half the width of the framework 1 and positioned so that it passes the other when the bearings 16 are in vertical alignment. The arm 3 in each case is attached to the center of the head and is bent outward at 22 towards the corresponding bearing. Uprights 23 extending from the frame 1 guide arms 17.

In the modification shown in Figure 4, the heads 24 are the full width of the framework. The arms 25 are not, therefore, centrally attached to the heads. This construction furnishes a more concentrated abrasive action over a given area but not as long a stroke of either brush. It will be understood that the stroke is so adjusted that the heads do not strike one another.

In either case, the overall width of the heads is greater than that of the framework so that the heads can be brought close to a wall.

Although specific embodiments of the invention have been illustrated and described, it will be understood that various alterations in the details of construction may be made without departing from the scope of the invention as indicated by the appended claims.

What I claim as my invention is:

1. In an abrasive machine, a portable frame, a shaft therein, means for driving said shaft, a pair of arms having crank connections to said shaft at points 180° apart with reference to the axis of said shaft, and abrasive heads rigidly secured to said arms and having convex floor-engaging surfaces, whereby to be rocked by actuation of said crank connections.

2. In an abrasive machine, a portable frame, a shaft therein, means for driving said shaft, a pair of arms having crank connections to said shaft at points 180° apart with reference to the axis of said shaft, and abrasive heads carried by said arms and having convex floor-engaging surfaces, whereby to be rocked by actuation of said crank connections, each head having substantially half

the width of said frame and positioned in end-to-end relation to the other, said crank connections having sufficient throw to cause said heads to pass each other.

3. In an abrasive machine, a portable frame, a shaft therein, means for driving said shaft, a pair of arms having crank connections to said shaft at points 180° apart with reference to the axis of said shaft, and abrasive heads carried by said arms and having convex floor-engaging surfaces, whereby to be rocked by actuation of said crank connections, said heads being substantially as wide as said frame and in end-to-end alignment in the direction of travel.

4. In an abrasive machine, a portable frame, a shaft therein, means for driving said shaft, a pair of arms having crank connections to said shaft at points 180° apart with reference to the axis of said shaft, and abrasive heads rigidly secured to said arms and having convex floor-engaging surfaces, whereby to be rocked by actuation of said crank connections, the overall width of said heads being slightly greater than that of said frame and symmetrical therewith.

5. In an abrasive machine, a portable frame, 25

a shaft therein, means for driving said shaft, a pair of arms having crank connections to said shaft at points 180° apart with reference to the axis of said shaft, and abrasive heads carried by said arms and having convex floor-engaging surfaces, whereby to be rocked by actuation of said crank connections, each head having substantially half the width of said frame and positioned in end-to-end relation to the other, said crank connections having sufficient throw to cause said heads to pass each other, the overall width of said heads being slightly greater than that of said frame and symmetrical therewith.

6. In an abrasive machine, a portable frame, a shaft therein, means for driving said shaft, a pair of arms having crank connections to said shaft at points 180° apart with reference to the axis of said shaft, and abrasive heads carried by said arms and having convex floor-engaging surfaces, 20 whereby to be rocked by actuation of said crank connections, said heads being slightly wider than said frame and symmetrical therewith and in end-to-end alignment in the direction of travel.
